UNITED STATES PATENT OFFICE.

LAWRENCE MERCER, OF WILBUR, WEST VIRGINIA.

WRENCH.

1,119,622.

Specification of Letters Patent.

Patented Dec. 1, 1914.

Application filed August 8, 1914. Serial No. 855,847.

To all whom it may concern:

Be it known that I, LAWRENCE MERCER, a citizen of the United States, residing at Wilbur, in the county of Tyler and State of 5 West Virginia, have invented certain new and useful Improvements in Wrenches, of which the following is a specification, reference being had to the accompanying drawings.

10 This invention comprehends certain new and useful improvements in quick acting wrenches of the sliding jaw type, and the invention has for its primary object a simple, durable and efficient construction of device 15 of this character in which the movable jaw may be very quickly adjusted to the work and then held in a securely fixed position in the operation of the tool. And the invention also aims to generally improve devices 20 of this class so as to render them more useful and commercially desirable.

With these and other objects in view, as will more fully appear as the description proceeds, the invention consists in certain 25 constructions, arrangements, and combinations of the parts that I shall hereinafter more fully describe and claim.

For a full understanding of the invention, reference is to be had to the following description and accompanying drawing, in 30 which,

Figure 1 is an edge view of a wrench embodying the principles and improvements of my invention; Fig. 2 is a side elevation 35 thereof partly in section; and Fig. 3 is a detail view of the locking pawl for the movable jaw.

Corresponding and like parts are referred to in the following description and designated in all of the views of the accompanying drawing by like reference characters.

Referring to the drawing, the numeral 1 designates the shank of my improved wrench, and 2 the handle thereof, the same 45 being of any desired construction or design.

3 designates the relatively fixed or stationary jaw of the wrench which is preferably formed integral with the shaft 1, and 50 4 designates the movable jaw which is mounted to slide on the shank, as shown. Preferably, both of these jaws are double and are formed on one side of the shank for engagement with nuts or the like and on the opposite side of the shank are provided with inset work engaging faces 5 which are trans-

versely serrated to adapt the wrench for use in connection with pipes or rods.

As clearly illustrated in the drawing, the relatively movable jaw 4 is formed with a longitudinally extended sleeve 6 and with a recess 7 at one end of said sleeve. In this recess a locking pawl or dog 8 is pivotally mounted at one end, said pawl being formed on one edge with transversely extending teeth 9 designed to engage with complementary teeth 10 on the shank 1, the sleeve 6 being formed for that purpose intermediate of its ends with an opening 11 into which the pawl 8 is designed to pass for the interlocking engagement of the teeth and for fixedly holding the movable jaw in its set or adjusted position.

The pawl 8 has secured thereto, on opposite sides, spring latch bars 12, the same being riveted or otherwise secured at one end on the opposite side faces of the pawl and extending rearwardly beyond the latter, the rear extremities of the latch bars being normally divergent as shown, and being designed to be pressed together by the operator's fingers, whereby they may pass in between hooked lugs 13 which are formed on the sleeve 6, these lugs together forming a keeper for the latch device comprised by the bars 12 and the latter being preferably formed in one edge with recesses 14 for engagement by the hooked or shouldered ends of the lugs.

From the foregoing description, in connection with the accompanying drawing, the operation of my improved wrench will be apparent. In the practical use of the device, when the pawl 8 is released and swung outwardly, it is clear that the movable jaw can be very quickly adjusted toward or away from the stationary jaw, as required, and then after the proper adjustment has thus been quickly secured, the rear relatively free extremities of the latch bars 12 may be easily pressed together and slipped in between the lugs 13 for engagement thereby so that the pawl will be securely held in locked relation to the shank and the movable jaw thus secured in position. Thus, it will be seen that I have provided a very simple and durable device which may be very quickly operated and the parts of which may be easily manufactured and readily assembled.

What I claim is:—

A wrench of the character described, in-

cluding a toothed shank, a fixed jaw, a movable jaw slidably mounted on the shank and provided with a sleeve encircling the latter, the sleeve being formed intermediate of its ends with an opening communicating with the toothed side of the shank, a pawl pivotally connected to said sleeve and provided with a toothed portion adapted to extend into said opening for engagement with the toothed side 5 of the shank, said pawl being provided with longitudinally extending and laterally spaced

resilient latch bars, and laterally spaced hooked lugs formed on said sleeve near said opening, and designed for engagement by said latch bars so as to hold the pawl in locking engagement with the shank. 15

In testimony whereof I hereunto affix my signature in the presence of two witnesses.

LAWRENCE MERCER.
